For a description of the invention, see the drawings and the following specification. It is to be understood that the invention is not limited to the exact construction shown, but includes all such modifications and changes as fall within the true spirit and scope of the invention.

It is an object of the invention to provide a hair curler which is simple, compact, and inexpensive to manufacture.

UNITED STATES PATENT OFFICE

2,092,578

HAIR CURLER

Frank Interrante, Brooklyn, N. Y.

Application November 8, 1935, Serial No. 48,838

3 Claims. (Cl. 132—40)

This invention relates to new and useful improvements in hair curlers.

The invention has for an object the construction of a device as mentioned which is characterized by a flexible hair retaining sheet for attachment at an inner portion on a transverse pliable holding strip and associated with a co-acting flexible hair retaining sheet and pliable elements on the outer ends of said sheets.

10 More particularly the invention proposes a novel construction and arrangement of the retaining sheets and the pliable elements.

One object of the invention is one in which the retaining sheets are separate and connected 15 along edge portions thereof.

Still further the invention proposes the construction of devices as mentioned which are simple and durable and which may be manufactured at reasonable costs.

20 For further comprehension of the invention, and of the objects and advantages thereof, reference will be had to the following description and accompanying drawing, and to the appended claims in which the various novel features of the 25 invention are more particularly set forth.

In the accompanying drawing forming a material part of the invention:—

Fig. 1 is a perspective view of a hair curler constructed according to this invention.

30 Fig. 2 is a vertical sectional view taken on the line 2—2 of Fig. 1.

Fig. 3 is a perspective view of a hair curler constructed according to another embodiment of the invention.

35 Fig. 4 is a vertical sectional view taken on the line 4—4 of Fig. 3.

The form of the invention shown in Fig. 1 comprises a flexible hair retaining sheet 10 for attachment on a transverse pliable holding strip

40 11. A co-acting flexible hair retaining sheet 12 is connected with said sheet 10.

The sheet 10 has its top portion 10' bent around the strip 11 and secured in fixed position by a line of stitches 14. The lower end of the sheet 45 10 is formed with the tubular portion 15 in which the flexible wire 13 is housed. The sheet 12 is connected with the sheet 10 by two areas of stitches 17 along the sides thereof at the free ends of the sheets. The lower end of the co-acting retaining sheet 12a has a tubular portion 15 in which the pliable wire 13 is housed.

50 This curler is used by inserting a lock of hair in the space between the pliable elements 13, then the sheet 12 is held against the hair and the strip 11 is wound so as to wind the sheets and the

hair into a curl. The hair is engaged into the curler with the tubular portion 15 toward the scalp, and the strip 11 acts as a roller to wind the sheets and the hair into a curl.

In Figs. 3 and 4 a modified form of the invention is shown in which the co-acting pliable sheet 12b is in the form of a very narrow strip which is attached at its ends by strip 18 to the lower edge of the sheet 10. In other respects this form of the invention is identical to the previous forms and corresponding parts may be recognized by the same reference numerals. The operation of this form of the device is similar to the operation of the form described in relation to the form illustrated in Figs. 3 and 4.

15 While I have illustrated and described the preferred embodiments of my invention, it is to be understood that I do not limit myself to the precise constructions herein disclosed and the right is reserved to all changes and modifications coming within the scope of the invention as defined in the appended claims.

20 Having thus described my invention, what I claim as new and desire to secure by United States Letters Patent is:—

25 1. A hair curler, comprising a flexible hair retaining sheet, a transverse pliable holding strip attached to the inner portion of said hair retaining sheet, a co-acting flexible hair retaining sheet super-imposed on said sheet, pliable elements on the outer ends of said sheet, stitches holding said sheets together near said pliable elements so that said sheets are open at their outer ends and partially open at their sides, whereby hair may be placed in between said pliable elements and between said sheets and said sheets rolled to form a curl and before and during rolling said hair may be correctly placed by engaging one's finger through said open sides.

30 2. A hair curler, comprising a flexible hair retaining sheet, a transverse pliable holding strip attached to the inner portion of said hair retaining sheet, a co-acting flexible hair retaining sheet superimposed on said sheet, pliable elements on the outer ends of said sheet, holding means for holding said sheets together near said pliable elements so that said sheets are open at their outer ends and partially open at their sides, whereby hair may be placed in between said pliable elements and between said sheets and said sheets rolled to form a curl and before and during rolling said hair may be correctly placed by engaging one's finger through said open sides.

35 3. A hair curler, comprising a flexible hair retaining sheet, a transverse pliable holding strip

attached to the inner portion of said hair retaining sheet, a co-acting flexible hair retaining sheet superimposed on said sheet, holding means for holding said sheets together near the outer ends of said sheets so that the said sheets are open at their outer ends and partially open at

their sides, whereby hair may be placed in between them and said sheets rolled to form a curl and before and during rolling said hair may be correctly placed by engaging one's finger through said open sides.
